Application February 9, 1938, Serial No. 189,525
 In Poland September 22, 1937

20 Claims. (Cl. 179—171)

The present invention relates to improvements in radio circuits and a method of operating the same, more particularly to frequency discriminating circuits designed to pass a predetermined range of signalling frequencies known as low-pass, high-pass, band-pass or band-elimination filters or networks in the art.

An object of the invention is to provide an improved band-pass type high frequency or intermediate frequency filter system with sharp cut-off properties such as for use as a selective system in the intermediate section of a superheterodyne receiver or in any other radio or electrical circuit.

18 A more specific object is the provision of a band-pass filter or network with a response or transmission band width which can be easily adjusted electrically by controlling an electric current or potential, either manually or automatically depending on the signal strength or any other controlling magnitude, to effect a band width or fidelity control in a radio or other signal receiver.

25 A further object is to provide a resonant system or filter circuit having a resonance or frequency response curve with ascending and/or descending branches of greatly increased steepness and requiring a limited number of circuit elements compared with circuits and systems 30 having similar characteristics known in the prior art.

35 Band-pass circuits or selectors as known in the art such as provided in the intermediate section of a superheterodyne receiver comprise two or more resonant circuits inductively or otherwise coupled with each other. Usually two coupled circuits are employed one of which is connected in the anode circuit of an amplifying valve and the other is connected in the grid circuit of the 40 succeeding amplifying valve of a cascade amplifier. In practice, at least two band-pass selectors of this type are required with pentode or other amplifying valves arranged therebetween in order to obtain a desired selectivity or cut-off effect. 45 This is equivalent to four tuned circuits connected in cascade, whereby in the case of the comparatively long wave lengths or low intermediate frequency commonly employed in superheterodyne systems the attenuation for signals 50 about 30 kc. of resonance is approximately 10 db. or more for each circuit, that is $10 \times 4 = 40$ db. total attenuation for all four circuits together. For the wave lengths in closer proximity to the resonance wave length, such as for a wave length 55 of about 10 kc. off resonance, the attenuation is

considerably less, in practical cases only about 3 db. for each circuit or a total attenuation of 12 db. or all four circuits combined. This attenuation is very low and in order to obtain in the latter case an attenuation of 40 db. for frequencies 5 10 kc. off the resonance point a prohibitive number of cascaded circuits or amplifying stages, in the example under discussion $40 \div 3$, i. e., 13 circuits, would be required. In other words, six band-pass twin circuits would be necessary with 10 five amplifying valves interconnecting the same. Furthermore, such a large number of circuits would entail a narrowing of the band-pass region 15 resulting in a cut-off or weakening the higher signal frequencies and in turn a substantial impairment of the fidelity of reproduction of the receiver.

By the present invention there is provided a filter or selective system requiring in its simplest form only a single composite or multiple amplifying valve with three to four tuned circuits and having a considerably improved selective or cut-off characteristic compared with circuits constructed according to the prior art methods embodying an equal number of valves and circuit 25 elements.

By a system according to the invention, an adjacent channel selectively can be obtained with a limited number of valves and amplifying stages equivalent to a cascade system of standard type 30 known in the art requiring about 20 circuits or 9 amplifying valves, with the further advantage that the band-pass region can be adjusted in any manner desired, that is without sacrifice of the fidelity of the received signal. In a system according to the invention embodying three filters 35 of the improved type in cascade, it can be shown that the adjacent channel selectively will become so high as to be practically unobtainable with any other system irrespective of its construction and 40 number of circuit elements and parts used.

As is known, the selectivity can be improved at the cost of the gain or degree of amplification of the system, that is if four circuits are connected between two amplifying valves each 45 coupled to the succeeding one, the selectivity is substantially higher than when only two coupled circuits are employed. However, the signal strength in the former case will drop considerably and in many cases cannot be offset by the 50 gain of the amplifying valves. Furthermore, every valve in a circuit of a receiver is subject to a certain extent to direct pick-up from interfering electro-magnetic fields. If a disturbing field 55 in a receiver has a field strength of about 100

microvolts and supposing the attenuation in the filter is such that the signal picked up from this field is decreased to about one microvolt and that simultaneously the direct pick-up produces a disturbing potential of about 100 microvolts on the grid of a valve, the high attenuating properties of the filters in such a case are substantially without use. The direct pick-up can of course be minimized by screening and shielding, but unless very careful screening methods are employed a certain amount of direct pick-up has always to be reckoned with.

From the above it follows that a specially advantageous and efficient filter should be constructed in such a manner as to attenuate all frequencies lying outside the band-pass region, but should not introduce appreciable attenuation for frequencies within the band-pass region. This requirement is fulfilled to a high degree by a filter of the type according to the present invention, which, while substantially improving the selectivity or cut-off characteristics also causes an increased gain for the desired frequencies, or at least acts to prevent appreciable attenuation of these frequencies.

Another characteristic of a filter of the type according to the invention, especially in the form of a band-pass filter, consists in the possibility of a simple and easy adjustment of the band width or frequency transmission characteristic. It is known that the band width or transmission characteristic of filters of known type can be adjusted by varying the degree of coupling between the circuits such as by moving the coupling coils towards or away from each other. In a band-pass filter of the type according to the invention this coupling is maintained constant and the band width of the filter adjusted by varying the relative magnitudes of the exciting potentials impressed upon the individual circuits of the filter system. This is accomplished in an easy and efficient manner by varying the gain or degree of amplification of one or all valves associated with each of the circuits of the filter system. In this manner automatic fidelity or selectivity control can be effected by using variable mu valves and adjusting the grid bias thereof either manually or in dependence of a control potential varying in accordance with the receiving signal field strength similar as in automatic volume control systems well known in the art. The selectivity control can further be combined with the volume control of the receiver in such a manner that the receiver automatically becomes highly sensitive and selective for weak and distant signals and less selective (increased fidelity) and less sensitive for stronger signals received from a local transmitter.

Band-pass filters according to the invention have a further advantage as described in the following. As is known, band-pass filters comprising a pair of coupled circuits can be easily and efficiently designed and constructed for frequencies of about 130 kc. or about 470 kc. employed at present as intermediate frequencies in superheterodyne radio broadcast receivers and with an effective band width or frequency response of about 10 kc. as required for distortionless reception of broadcast signals. For the higher frequencies, however, for instance 1600 kc. such filters would have a band width of about 40 kc. or more and would no longer be selective for receiving signals comprising a 10 kc. frequency band. A filter constructed according to the invention, however, can be designed for practically

any frequency and band width; that is, the filter can be designed for 0.2 kc. band width at 100 kc. or for 10 kc. band width at 1600 kc. Moreover, the filter according to the invention can be tuned and adjusted by the normal methods which is not the case with other and more complicated filter systems. If an especially sharp cut-off is required for the filter, one or more resonant circuits of the filter may have quartz crystal resonators suitably connected therewith.

It is furthermore possible to combine a filter of the type according to the invention with filters of known construction, especially filters comprising two or more coupled circuits to obtain the benefits and advantages of the invention.

The above and further objects of the invention will become more apparent from the following detailed description taken with reference to the exemplifications of the invention illustrated by the accompanying drawings forming part of this specification and wherein—

Figure 1 is a simple circuit diagram of a selective amplifier and filter system constructed in accordance with the invention.

Figure 2 shows a number of resonance curves illustrative of the function of the circuit according to Figure 1.

Figure 3 is a diagram combining a pair of filter systems of the type shown in Figure 1 to secure a band-pass response characteristic.

Figure 4 shows the resonance curves for the circuit according to Figure 3.

Figure 5 illustrates an alternative system for obtaining a band-pass effect.

Figure 6 shows the resonance curves for the circuit according to Figure 5.

Figure 7 is a diagrammatic representation of a multiple valve adapted for use in a filter system of the type according to the invention.

Figure 8 is a vertical cross-section through a practical embodiment of a valve as illustrated in Figure 7.

Figure 9 is a horizontal cross-section through the valve shown in Figure 8.

Figure 10 is a partial perspective view of Figure 8 showing the mounting of the separate anodes.

Figure 11 illustrates a practical construction of a coupling coil system for use in a filter circuit according to the invention.

Figure 12 is a complete circuit diagram of a superheterodyne radio receiver embodying band-pass filters and selective circuits as well as automatic selectivity control in accordance with the invention, and

Figure 13 shows resonance curves for the circuit according to Figure 12.

Similar reference characters designate similar parts throughout the different views of the drawings.

Referring to Figure 1 of the drawings, there are shown two amplifying valves 10 and 11 of known construction having, in the example illustrated, cathodes, control grids, screen grids and plates or anodes and having their grid circuits excited from a common source 12 of high frequency or low frequency energy through a coupling transformer comprising a primary 13 and secondary 14, grid coupling condensers 15 and 16 and grid leak resistances 17 and 18, respectively. The grid leaks 17 and 18 may be connected to suitable biasing sources to provide suitable operating grid bias for the valves. There is further shown a tunable circuit comprising a condenser 19 shunted by an inductance coil 20 in series with a further inductance coil 21, inserted

in the plate circuit of valve 10, and a similar tunable circuit comprising a condenser 22 shunted by an inductance 23 in series with an additional inductance coil 24 connected in the anode circuit 5 of the valve 11. The anodes of the valves are connected to the positive pole of a high potential source indicated by the plus symbols in a known manner, further well known details such as the return leads to the cathodes and grids having 10 been omitted for simplicity of illustration.

The coils 21 and 24 which may form a part of the inductances 20 and 23 or, as in the example shown may be separate coupling coils in series with the inductances 20 and 23, respectively, are 15 arranged in inductive coupling relation with each other. The amplified signal currents are impressed upon a subsequent circuit or apparatus such as a further amplifier or detector or the like through a coupling condenser 25 connected 20 to the anode of valve 10.

Let it be assumed for the sake of explanation that the circuit 22, 23, 24 is removed and that a resonance curve (signal response in db. or any other unit as a function of the frequency f) is 25 plotted for the circuit 19, 20 and 21 by varying the frequency of the source 12. In this case, a resonance curve of known shape will be obtained as shown at A of Figure 2. If the second circuit 22, 23, 24 is now coupled to the circuit 19, 20 30 and 21 in the manner shown and tuned such as by adjusting the condenser 22, the signal or current in the circuit 19, 23 and 21 will increase and its frequency response or resonance characteristic will be changed as shown by the curve B in Figure 2. If subsequently the excitation of the circuit 22, 23, 24 is reduced such as by controlling 35 the gain of the valve 11 by adjustment of the grid bias—for which purpose preferably a variable mu valve is employed—the frequency characteristic or resonance curve for the circuit 19, 20 and 21 will assume a shape as shown at C in Figure 2. From this it is seen that the effect of the circuit 22, 23, 24 excited separately from the same input circuit or signal source 12 through 40 an individual amplifier (valve 11), in the first place results in an increase of the desired frequency or signal strength and in the second place in a rejector effect at one side of the resonance curve for a frequency adjacent to the desired or 45 resonance frequency or in other words, in a sharp cut-off effect close to the resonant frequency. Moreover, by varying the exciting potential impressed upon the circuit 22, 23, 24 the amount of 50 the improvement (gain and rejector effect) can be controlled within a substantial range to obtain a desired shape or sharpness of the resultant resonance characteristic.

In most practical cases it is desirable to obtain 55 the above rejector effect or sharp cut-off at both sides of the resonance point, that is to secure a true band-pass response, especially for use in a radio receiver or similar signalling device. Such a band-pass effect can be obtained according to a further feature of the invention by employing 60 two circuits of the type as shown in Figure 1 in cascade or in parallel wherein the first circuit is designed to produce a rejector effect at one side of the resonance frequency and the second circuit is designed to produce a rejector effect on 65 the other side of the resonance frequency, in such a manner as to obtain a resultant band-pass response characteristic.

Referring to Figure 3 showing an arrangement 70 of this type, the first stage of the system comprising the valves 10 and 11 and associate reso-

nant plate circuits 19, 20, 21 and 22, 23, 24, respectively, are substantially identical to Figure 1. There is further shown a second stage similar to the first one comprising a pair of valves 33 and 34 both coupled to the anode of valve 10 5 through coupling condensers 25 and 23, respectively. Both valves have associated therewith resonant plate circuits, the first comprising a condenser 35 shunted by an inductance coil 36 in series with a coupling coil 37 and the second 10 comprising a condenser 38 shunted by an inductance coil 39 in series with a coupling coil 40. The coils 37 and 40 are inductively coupled with each other in a sense opposite to the coupling of the coils 21 and 24 in the first stage, thereby obtaining a rejector or cut-off effect at both sides of the resonant frequency in the output circuit of the system. The signals are applied to a further circuit or translating device through a coupling 15 condenser 41 connected to the anode of valve 33. 20 There are further shown in Figure 3 a pair of potentiometers 30 and 31 connected to the grids of valves 10, 33 and 11, 34, respectively, for adjusting the gain and rejector effect in both stages 25 in a manner described hereinabove.

Referring to Figure 4 there is shown at A a resonance curve for the circuit 35, 36, 37 taken independently which is similar to curve A in Figure 2; B' is the resonance curve for the circuit 35, 36, 37 before adjustment of the gain of the valves 30 and 31, and C' represents the resonance curve after adjustment of the grid bias or gain in the amplifying stages. These curves have true 30 band-pass characteristics with a sharp frequency 35 cut-off at both sides of the resonant frequency.

Instead of using two stages in cascade as shown in Figure 3, three or more parallel circuits connected to a common output circuit as shown in Figure 5 may be used to obtain an improved band-pass response in a system constructed in 40 accordance with the invention. In the figure, valves 10 and 11 and the associated plate circuits are substantially similar to Figure 1. In addition, a further valve 44 is excited from the secondary 44 of the input transformer through 45 a coupling condenser 45 and grid leak resistance 46. Valve 44 has a resonant circuit inserted in its plate circuit comprising a condenser 47 shunted by an inductance coil 48 in series with a coupling coil 49, the latter being in inductive 50 coupling relation with a further coupling coil 50 serially arranged with the inductance 23 of the plate resonant circuit associated with the valve 11. The couplings 21, 24 and 49, 50 correspond 55 to the couplings 21, 24 and 31, 40 in Figure 3 and are such as to impress potentials of opposite phase upon the circuit 22, 23, 24, 50 resulting in an improved cut-off effect on both sides of the resonance curve. The output signals may be 60 derived in the same manner as shown in Figure 1 from the anode of valve 11 through a coupling condenser or the like. Alternatively, as shown in the example illustrated a further resonant circuit is provided comprising an inductance coil 51 coupled with the inductance 23 of the plate resonant circuit of the valve 11 and shunted by a condenser 52. In this manner the selectivity of 65 the system is further improved by a combination of the inventive circuit with a normal twin 70 coupled circuit (22, 23, 24, 50 and 51, 52).

The resonance curves for Figure 5 are shown in Figure 6. In the latter D represents the resonance curve for the highest amplification or gain and narrow band width; E is the curve for lowest 75 amplification and greatest band width; and F

corresponds to an intermediate adjustment, any of these curves or any intermediate curve being easily obtainable by adjusting the gain of the amplifiers of the valves 10, 11 and 44. A in Figure 6 represents for comparison the individual resonance curve for the single circuit 22, 23, 24, 50 similar as in Figures 2 and 4.

In arrangements of the above described type an increased number of amplifying valves may be

- 10 required. In order to limit the number of valves according to a further feature of the invention, composite or multiple valves constructed in a known manner with a sub-divided anode structure may be employed in connection with filter 15 circuits according to the invention. Such a valve of the pentode type which may be used in connection with Figure 5 is diagrammatically shown in Figure 7 and comprises a common vessel or envelope 55, a heater 56, common cathode 57, common control grid 58, common screen grid and suppressor grids 59 and 60, respectively, and three 20 separate anodes 61, 62, 63, arranged in such a manner as to provide three separate discharge paths from the cathode 57 simultaneously controlled by the grid 58. In place of a pentode type valve any other type may be constructed in this manner for use in connection with the invention, such as an ordinary three element amplifier 25 valve or triode, a converter or mixer valve as shown 30 in Figure 12 or a valve of any other type. If a composite valve is to be used in a circuit according to Figure 1, it is understood that only two anodes are required.

Referring to Figures 8 to 10, there is shown a practical construction of a valve of the type according to the diagram of Figure 7. The cathode 57 has the form of an oblong cylinder coated with thermionically active material at the respective discharge sections and surrounded by a concentric spirally shaped control grid, a screen grid and a suppressor grid 58, 59, 60, respectively, and by three separate concentric cylindrical anodes 61, 62, 63 supported by rods 66, 67, 68, respectively, the latter being secured to spacing mica discs or 45 supports 64 and 65 in a manner well known in the construction of discharge devices.

If a valve of this type is to be used for band width adjustment as described hereinabove, several winding turns maybe omitted in the control grid to provide a variable mu characteristic for the particular section of the valve. In the example illustrated, the portion of the control grid opposite the anodes 61 and 63 have a greater controlling effect than the portion of the grid opposite the anode 62. This is obtained by varying the numbers of turns in the respective control grid portions such as by omitting two turns in the central portion of the control grid and omitting one turn in the outer portion of the control grid as shown in the drawings. In this manner, if the bias of the control grid 58 is increased, the amplification of the section of the valve enclosed by the anode 62 will decrease to a lesser degree than the amplification of the sections enclosed by the anodes 61 and 63, whereby the over-all amplification of the receiver and with it the band width of the system can be controlled easily. As is understood, any other known method to obtain a variable mu effect can be used, such as a variation in the winding pitch of the respective grid sections. It is only essential for the invention that the variable mu characteristic is different for different discharge portions within the valve to obtain different degrees of control for the 75 separate discharge paths. In order to screen the

separate anodes from each other a separate screen may be used as indicated in Figure 7 or the suppressor grid 60 may be constructed in a suitable manner to screen the anodes both from the rest of the tube elements and from each other. As will be understood, any other type of valve may be constructed in the manner described for use in a filter system according to the invention.

Referring to Figure 11, there is shown by way of example, a construction of the coil arrangement as shown in Figure 5. The entire unit is surrounded by a metallic enclosure 72. The inductance 23 of the central circuit comprises two sections 23 and 23' the latter having a smaller number of turns and serving as a coupling element in inductive coupling relation with the inductance 51 of the associated resonant circuit. In order to decrease the coupling between the coils 20, 23 and 48, metal rings or discs 70 and 71 consisting preferably of copper may be mounted 20 between the coils. These rings may be further arranged for adjustment in order to effect or correct the tuning of the circuits and obtain a most favorable operating characteristic. The coils 23' and 51 are shown screened by a separate compartment 53 within the main screen 72, but if desired can be arranged separately and screened or shielded individually. There are further provided leads 74, 75, 76 and 77 for connecting the separate coils in the circuit shown in Figure 5.

In order to obtain a sharp cut-off characteristic it has been found that the additional circuits (22,

23, 24 according to Figures 1 and 3, 38, 39, 40 according to Figure 3, and 19, 20, 21 and 47, 48, 49 according to Figure 5) should preferably be less 35

damped than the main circuits (19, 20, 21 according to Figures 1 and 3, 35, 36, 37 according to Figure 3, and 22, 23, 24, 50 according to Figure 5). On the other hand, if the damping is substantially reduced, the saddle in the curve B' according to 40

Figure 4 will become more pronounced. This can be avoided if an additional ordinary filter circuit is connected to the inventive circuit such as shown in Figure 5 (circuit 51, 52). In the latter case the resonance curves will be of the type 45

shown in Figure 6. Moreover, the saddle in curve B' according to Figure 4 can be removed and a square-top curve obtained with reduced band width if the additional circuits (22, 23, 24, etc.), are detuned to a substantially lesser degree. Ex- 50

tremely sharp characteristics with very narrow band width can be obtained by embodying quartz crystal resonators in the additional circuits 22, 23, 24, etc., such as by the provision of high fre- 55

quency choke coils in the anode circuits of the valves 10 and 44, Figure 5, and by feeding the circuits 19, 20, 21 and 47, 48 through condensers and/or the quartz crystals. By means of such crystals sharp cut-offs are obtained equivalent 60

to the sharpness of ordinary circuits using quartz crystals but with a flat top resonant curve and a band width substantially wider than can be obtained with a single circuit of known type embodying quartz crystal resonators. If greater 65

band widths are required the damping of all circuits used in the filter unit should be higher. From this, it is obvious that any desired frequency characteristic may be obtained in ac- 70

cordance with the invention for any frequency by reason of the fact that the additional circuits also increase the volume of the signals thereby increasing the over-all efficiency or amplification of the system.

The adjustment of a filter system of the invention is extremely simple. Thus, in an arrange- 75

ment according to Figure 3, first the condensers 22 and 38 are detuned to a substantial degree, that is adjusted to zero capacity to eliminate the effect of the additional circuits upon the main circuits. The latter are then tuned to resonance. Thereupon, the circuit 22, 23, 24 is tuned so as to increase the current or potential in the output circuits connected to points 41 and 41' and finally the circuit 38, 39, 40 is tuned while observing the increase of the output current. During the tuning of the additional circuits, it will be noted that by increasing the capacity of the condenser, the signal will first disappear and then after further increase of the capacity will reappear with substantially greater volume. If the coupling is reversed, that is as shown at 37 and 40 in Figure 3, the behavior of the additional circuit 38, 39, 40 will be opposite, that is if the condenser 38 is increased at first the volume of the signal will increase and then disappear for a certain capacity of the condenser 38. The explanation for this is the fact that the rejective effect now occurs on the other side of the resonance curve. This reversing of the coupling of the filter unit such as for the coils 20 and 48, Figure 11, may also be effected by reversing the anode or high tension connections of the respective circuits, that is by reversing the relative phase of the exciting potentials by 180°.

30 The filters can be more accurately tuned and adjusted by means of an oscillographic method whereby the resonance curves may be directly viewed on the screen of a cathode ray tube or the like. In this latter case also, at first the main 35 circuits are tuned and then the auxiliary circuits adjusted in the manner described above or both circuits may be adjusted simultaneously until the proper resonance curve appears on the screen of the cathode ray tube. In order to obtain an adequate band-pass action with a sharp cut-off effect, the coupling between the circuits should be correct. Thus the coupling between the circuit 22, 23, 24, 50 and 51, 52, Figure 5, should be considerable higher than is used in band-pass filters 40 of usual construction. The coupling between the additional or auxiliary circuits 47, 48, 49 and 19, 20, 21, Figure 5, and the main circuit 22, 23, 24, 50 should preferably be such that $M\omega = \sqrt{R_1 R_2}$ 45 wherein M represents the coefficient of mutual inductance between the circuits, ω is the frequency of the signals in radians per second, R_1 represents the ohmic or loss resistance in the main circuit 22, 23, 24, 50 and R_2 the corresponding resistance in the additional circuits 19, 20, 50 21 and 47, 48, 49.

55 From the above it follows if the circuits 19, 20, 21 and 47, 48, 49 are lowly damped, a rather low coupling is required and care should be taken that no other spurious coupling occurs beyond a permissible limit in the external circuit connections or through the valves between the circuits. For this reason every circuit in the inventive system is associated with a special exciting valve or a separate plate of a composite or multiple valve 60 of the type described. Moreover, as previously explained, the connection of the additional circuits with separate valves or a valve with a plurality of anodes has the advantage of enabling an easy adjustment of the band width according to a further feature of the invention. Since the 65 circuits of the filter unit are coupled with each other, they may be placed in a screened container as shown in Figure 11 or in two or more containers if desired.

70 Resonance curves of the type shown at B or

C', Figure 2, may be very useful for demodulation of frequency modulated signals. For this purpose the steep rectilinear portion of the curve B may be utilized and the operating point for the unmodulated carrier adjusted in a manner to fall 5 within the steep rectilinear portion of the characteristic. The steepness of the curve and accordingly, the efficiency of the demodulation can be further increased by using two or more circuits in cascade such as shown in Figure 5 in 10 which case, however, the coupling 37, 40 should not be reversed as previously described where a band-pass effect is desired. Furthermore, a system according to Figure 5 may be used to secure 15 a steep characteristic for demodulation of frequency modulated signals in which case the third valve 44 and associated circuit 47, 48, 49 may be dispensed with as will be understood. The steepness of the curve B can further be increased by 20 employing a greater number of twin parallel circuits in cascade such as shown in Figures 1 and 3. The adjustment of the grid bias in proportion to the variations of the strength of the received signals in this case provides an efficient control 25 of the steepness of the resonance curve and may be used for pure volume control of the frequency modulated signals.

Referring to Figure 12 there is shown a complete diagram of a superheterodyne radio receiver 30 incorporating filters with composite valves and automatic volume and selectivity control according to the invention. There is shown an antenna circuit comprising an antenna 80, antenna coupling condenser 81, coupling coil 82 and ground connection 87. Coil 82 is coupled with a filter 35 of usual design comprising a first resonant circuit constituted by an inductance 83 shunted by a capacity 85 and a secondary resonant circuit comprising an inductance coil 84 shunted by a condenser 86. The antenna coupling coil is in 40 coupling connection with either or both of the inductance coils 83 and 84 of the resonant circuits. The circuit 84, 86 serves to excite the input or signal control grid 93 of a composite mixer or frequency converter valve 89 of otherwise 45 usual construction having a cathode 90, oscillator control grid 91, oscillator or anode grid 92, signal input grid 93 enclosed by a screen grid 94 and three separate anodes 95, 96 and 97 mounted and arranged relative to the other electrodes in a 50 manner substantially as described in connection with Figures 8 to 10. The cathode 90 is connected to ground through a biasing resistance 99 shunted by by-passing condenser 100 to provide adequate operating grid biasing potential for the 55 signal input grid 93. The screen grid 94 is connected to the plus terminal of a high tension source indicated by the plus symbol through a voltage drop resistance 101 and to ground through a decoupling condenser 101' in the manner well known. The oscillating grid 91 is connected to an oscillating tank circuit comprised of an inductance 102 shunted by a variable condenser 103 through a coupling arrangement consisting of a grid coupling condenser 104 and grid 60 leak 105. In order to maintain sustained local oscillations in the tank circuit 102, 103, a feedback coil 106 inductively coupled with the inductance 102 is connected in the lead from the positive or anode grid 92 to the positive pole of 65 the high tension source through drop resistance 107. The lower end of the latter is shunted to ground through a by-pass condenser 108. In this manner, sustained oscillations are maintained in the oscillator tank circuit 102, 103 with the steady 70 75

bias for the oscillating grid 91 being produced by the direct current drop through the grid leak 105. The oscillating condenser 103 is ganged and tracked in the usual manner with the input tuning condensers 85 and 86 by mounting upon a common shaft as indicated at 132 to maintain a constant frequency differential equal to the intermediate frequency of the system obtained in the output circuit of the valve by the modulating or mixing action of the latter.

The central anode 96 is connected to one terminal of a resonant circuit comprising an inductance coil 110 in series with a pair of coupling coils 111 and 112, and shunted by a condenser 113. The other terminal of the resonant circuit is connected to the positive pole of the high tension source through a resistance 114 by-passed by a condenser 115. The anode 95 is connected to one terminal of a parallel tuned circuit comprising an inductance 116 in series with a coupling coil 117 and shunted by a condenser 118, the other terminal of the circuit being connected to the positive pole of the high tension source through a resistance 119 by-passed by a condenser 120. Furthermore, the anode 97 is connected to one terminal of a parallel tuned circuit comprising an inductance coil 121 in series with a coupling coil 122 and shunted by a condenser 123, the other terminal of the circuit being connected to the positive pole of a high tension source through a resistance 124 by-passed by a condenser 125. There is further shown a resistance 126 connected between the positive pole of the high tension source and the cathode 90 to stabilize and fix the cathode potential. The coupling coils 111, 117 and 112, 122 are in inductive relation with each other thereby forming a filter system together with valve 89 substantially similar as shown in Figure 5. As is understood, the circuit 110, 111, 112, 113, circuit 116, 117, 118 and circuit 121, 122, 123 are tuned in respect to the intermediate frequency of the system obtained by the mixing or frequency changing action of the valve 89.

The inductance 110 of the tuned anode circuit connected to anode 96 is coupled with the inductance 130 of a resonant input circuit for an intermediate frequency variable mu type amplifying valve 132 also constructed as shown in Figures 7 to 10. The input circuit of this valve is completed by the condenser 131 shunting the inductance 130. The valve 132 includes a control grid 133 connected to the upper terminal of the input circuit 130, 131, a screen grid 134 connected to the positive pole of the high tension source through a resistance 135 shunted by a condenser 136, a suppressor grid connected to the cathode in a known manner and three anodes 137, 138 and 139. The cathode of the tube is connected to ground or the negative potential point of the system through a biasing resistance 140 shunted by a by-pass condenser 141. The anodes 137, 138, 139 are connected to three interconnected resonant circuits similar as shown in Figure 5, the resonant circuit inserted in the circuit of anode 137 comprising an inductance coil 142 in series with a coupling coil 143 and shunted by a condenser 144, the resonant circuit inserted in the circuit of anode 138 comprising an inductance coil 146 in series with a pair of coupling coils 147 and 148 and shunted by condenser 149, and the resonant circuit inserted in the circuit of anode 139 comprising an inductance 150 in series with a coupling coil 151 and shunted by condenser 152. Coil 143 is in coupling relation with the coil 147 and coil 148 is in coupling relation with coil

151. The cathode of the valve 132 is connected to the positive pole of the high tension source through a resistance 153 by-passed by condenser 154 to stabilize the steady or quiescent cathode potential. A resonant circuit comprising an inductance coil 155 shunted by a condenser 156 is coupled with the central filter circuit 146, 147, 148, 149 in a manner similar as in the previously described arrangements. This resonant circuit serves to excite a duplex-diode valve 160. For this purpose the upper terminal of the circuit is connected to the anode of one of the diode sections and the lower terminal is connected to the grid of the valve 160 through a coupling condenser 161 and a grid leak 162. The lower terminal of the circuit 155, 156 is further connected to ground through a resistance 163 shunted by a condenser 164 to form a coupling impedance network for applying the low frequency or demodulated signal potentials generated by rectification to the grid of the valve for further amplification in the output circuit. The cathode of the valve is connected to ground through a biasing resistance 165 by-passed by condenser 166 to provide adequate operating grid biasing potential. The amplified demodulated or low frequency signals are applied from the anode of the valve 160 through a low frequency or audio transformer having a primary 175 and a secondary 176 to a pair of further audio frequency amplifier valves connected in push-pull in a known manner and serving to operate a translating device such as a dynamic loud speaker 186 through an output push-pull transformer having a primary winding 184 and secondary winding 185. The anode of valve 160 is connected through the primary 175 to the positive pole of the high tension source in series with a resistance 177 by-passed by a condenser 178. There is further provided a shunt circuit from the anode of valve 160 to ground comprising a variable resistance 173 and a condenser 174 in series and serving as a tone control circuit in a manner well known. The center point of the secondary of the push-pull input transformer is connected to ground through a resistance 181, and the common cathode point 45 of the push-pull amplifier valves 179 and 180 is connected to ground through a grid biasing resistance 182 by-passed by a condenser 183. The anode potential for the valves 179, 180 is supplied direct from the high tension source to the center point of the primary 184 of the push-pull output transformer which center point is bypassed to ground by a condenser 187.

The second anode of the valve 160 is utilized to generate a volume or selectivity control potential and for this purpose is connected to the upper terminal of the central resonant circuit of the filter system 146, 147, 148, 149 through a coupling condenser 167 on the one hand, and to ground through a pair of resistances 168 and 169 in series. In this manner, there is produced at the junction of the resistors 168, 169 a steady potential varying in accordance with the field strength or carrier amplitude of the signals received in the input circuit. This potential is applied to the control grids 93 and 133 of the valves 89 and 132 through resistances 172 and 178, respectively connecting the junction between the resistances 168 and 169 to the lower terminals of the input circuits 84, 86 and 130, 131, respectively, thereby completing the cathode return for the latter. In this manner combined automatic volume and selectivity or fidelity control of the receiver is effected as described hereinbefore. In addition, the bias resistors 99 and 140 inserted in the cathode leads 75

of the valves 89 and 133 are shown to be variable and arranged for common control by a coupling element indicated at 189 to allow for manual adjustment of the volume and fidelity level of the receiver in addition to the automatic adjustment described.

The over-all fidelity and volume control curves for a receiver of this type are shown in Figure 13 wherein curve G is the over-all resonance characteristic of the receiver for high gain and high selectivity, J the resonance curve for low gain and low selectivity or high fidelity, and H a curve for an intermediate adjustment.

A system equipped with combined automatic volume and selectivity control of the type described has the further advantage that the volume control ratio is substantially higher than in the ordinary automatic volume control systems known. The standard variable mu valves used in the commonly known circuits allow of a variation over a range of about 35 db. per valve. In systems with combined volume and selectivity control of the type according to the invention, this control range is increased to about 35 to 40 db. by reason of the fact that the additional circuits act to increase the apparent Q or coefficient of merit

$$\left(\frac{L\omega}{R} \right)$$

of the main circuit with low grid bias values of the amplifying valves. For strong signals the amplification of the valves is reduced and with it the Q of the main circuit due to the fact that in this case the additional circuits have the effect of increasing the damping of the main circuit. This feature of automatically varying the Q factor of a circuit is an important characteristic of the invention.

In modern radio receivers, it is customary to provide an automatic tuning arrangement in addition to automatic volume control and/or fidelity control. In general, arrangements of this type operate in such a manner that after the receiver has been tuned approximately to a desired station, either by hand or a dialing or push-button mechanism, the automatic tuning system is set in operation and acts to adjust the heterodyning frequency of the local oscillator in such a manner that the intermediate signal frequency coincides exactly with the center or resonance point of the characteristic of the tuned intermediate frequency amplifier. In order to generate a tune responsive or discriminating potential for adjusting the oscillating frequency in a system of this type, it has been proposed to provide two detuned circuits, one slightly tuned below and the other slightly tuned above the intermediate frequency of the receiver from which circuits a direct potential is derived by rectification and differential combination varying in either a positive or negative direction in dependence of the degree of detuning of the signal above or below the intermediate frequency, respectively, for which the receiver is designed. If automatic frequency control of this type is used in a circuit according to the invention, such as described, the detuned or discriminating circuits may be combined with the additional circuits, according to Figure 12 (circuits 142, 143, 144, and 150, 151, 152). In this manner a substantial saving in parts and apparatus can be effected while obtaining the combined benefits of automatic volume, automatic frequency and automatic fidelity control in a radio receiver.

It will be obvious from the above that the in-

vention is not limited to the specific arrangement of parts and elements shown and methods disclosed herein for illustration, but that the underlying inventive thought and principle are susceptible of numerous modifications and variations differing from the embodiments described and coming within the broader scope and spirit of the invention as defined in the appended claims.

The specification and drawings are accordingly to be regarded in an illustrative rather than a limiting sense.

I claim:

1. An electric translation system comprising an input circuit, an output circuit, a plurality of amplifiers arranged in parallel and excited from said input circuit, a tunable resonant circuit in the output of each of said amplifiers, said tunable circuits being coupled in pairs and their frequency resonance curves being substantially equal, and coupling means between said output circuit and one of said tunable circuits.

2. An electric translation system comprising an input circuit, an output circuit, a plurality of amplifiers arranged in parallel and excited from said input circuit, a tunable resonant circuit in the output of each of said amplifiers, said tunable circuits being coupled with each other and their frequency resonance curves being substantially equal, said tunable circuits being tuned to different resonant frequencies so that their frequency resonance curves overlap, and coupling means between said output circuit and one of said tunable circuits.

3. An electric translation system comprising an input circuit, an output circuit, a plurality of amplifiers arranged in parallel and excited from said input circuit, a tunable resonant circuit in the output of each of said amplifiers, said tunable circuits being coupled with each other and having substantially equal resonance curves, said tunable circuits being tuned to slightly different resonant frequencies, coupling means between said output circuit and one of said tunable circuits, and means for adjusting the gain of at least one of said amplifiers to vary the over-all resonance characteristic of the system.

4. An electric translation system comprising an input circuit, an output circuit, a plurality of amplifiers with means for simultaneously exciting the same from said input circuit, tunable circuits in the outputs of said amplifiers inductively coupled with each other sufficiently closely to effect a mutual interchange of resonant energy therebetween when simultaneously excited by similar potentials, coupling means between one of said tunable circuits and said output circuit, the remaining tunable circuits being detuned relative to said first mentioned tunable circuit to obtain a resultant frequency response characteristic of said system having a sharp cut-off close to the resonant frequency of said first tunable circuit, and means for adjusting the gain of said amplifiers.

5. A signal translation system comprising an input circuit, a resonant output circuit, a first resonant circuit, coupling means between said first resonant circuit and said output circuit, at least one further resonant circuit coupled with said first resonant circuit, said coupled first and further resonant circuits having substantially equal resonance curves, and individual unilateral signal transmission paths from said input circuit to said first and further resonant circuits.

6. A signal translation system comprising an

- input circuit, an output circuit, a first tunable resonant circuit, coupling means between said tunable circuit and said output circuit, at least one further tunable resonant circuit arranged in inductive coupling relation with said first tunable circuit, the mutual coupling impedance (M_o) between said tunable circuits being equal or less than the square root of the product of their non-reactive impedances, the frequency response characteristics of said first and further circuits being substantially equal, and individual uni-lateral signal transmission paths from said input circuit to each of said tunable circuits.
7. A signal translation system comprising an input circuit, an output circuit, a first tunable resonant circuit, coupling means between said tunable circuit and said output circuit, at least one further tunable resonant circuit in inductive coupling relation with said first tunable circuit, the mutual coupling impedance (M_o) between said tunable circuits being equal or less than the square root of the product of their non-reactive impedances, the frequency response characteristics of said first and further circuits being substantially equal, separate amplifiers connected between said input circuit and each of said tunable circuits, and means for adjusting the gain of said amplifiers.
8. A signal translation system comprising an input circuit, an output circuit, a main resonant circuit, coupling means between said resonant circuit and said output circuit, at least one auxiliary resonant circuit coupled with said main resonant circuit and having a damping coefficient greater than the damping coefficient of said main resonant circuit, said coupled main and auxiliary resonant circuits having substantially equal frequency response characteristics and being tuned to slightly different resonant frequencies, the resonant frequency of said main resonant circuit substantially equaling the signal frequency, and a plurality of amplifying valves individually connecting said input circuit with each of said resonant circuits.
9. A signal translation system comprising an input circuit, an output circuit, a main resonant circuit, coupling means between said main resonant circuit and said output circuit, further auxiliary resonant circuits coupled with said main resonant circuit sufficiently closely to effect an interchange of resonant energy between said circuits when all of said circuits are simultaneously excited by similar potentials, and a plurality of amplifying valves individually connecting said input circuit with each of said main and auxiliary resonant circuits, the coupling of at least two of said auxiliary resonant circuits with said main resonant circuit being such as to impress potentials of opposite phase upon said main resonant circuit.
10. A translation system for modulated carrier signals comprising an input circuit, an output circuit, a main resonant circuit, coupling means between said main resonant circuit and said output circuit, a plurality of auxiliary resonant circuits coupled with said main resonant circuit, a plurality of amplifying valves individually connecting said input circuit with each of said main and auxiliary resonant circuits, means for controlling the gain of said amplifiers, the coupling of at least two of said auxiliary resonant circuits with said main resonant circuit being such as to impress potentials of opposite phase upon said main resonant circuit, thereby to obtain a resultant input-output frequency response charac-
- teristic with a sharp cut-off at both sides of the resonant frequency of said main resonant circuit taken individually.
11. In a system as claimed in the preceding claim including means for generating a control potential varying in accordance with fluctuations of the carrier amplitude, and means for applying said potential to a gain control means of said amplifiers.
12. A translation system for modulated carrier signals comprising an input circuit, a resonant output circuit, a main resonant circuit, coupling means between said main resonant circuit and said output circuit, at least two auxiliary resonant circuits sufficiently closely coupled with said main resonant circuit to effect a mutual interchange of resonant energy therebetween when said circuits are simultaneously excited by similar potentials, a plurality of electronic amplifying paths having input and output electrodes, said input electrodes being connected to said input circuit and each of the output electrodes being connected to one of said main and auxiliary resonant circuits, the coupling between said auxiliary resonant circuits with and the tuning thereof relative to said main resonant circuit and the gain of said amplifying paths being such as to obtain a sharp cut-off at both sides of the resonance characteristic of said main resonant circuit in respect to signals applied to said input circuit.
13. A translation system for modulated carrier signals comprising an input circuit, an output circuit, a main resonant circuit, coupling means between said main resonant circuit and said output circuit, at least two auxiliary resonant circuits sufficiently closely coupled with said main resonant circuit to effect a mutual interchange of resonant energy therebetween when said circuits are simultaneously excited by similar potentials, a plurality of electronic amplifying paths each comprising a cathode, an anode and a control electrode, coupling connections from said input circuit to the control electrodes of said amplifying paths, each of said main and auxiliary resonant circuits being connected in the anode circuit of one of said amplifying paths, the coupling between said auxiliary resonant circuits and said main resonant circuit, the tuning of said auxiliary resonant circuit relative to the tuning of said main resonant circuit and the relative gain of said amplifying paths being such as to cause a resultant characteristic of said main resonant circuit having a sharp cut-off at both sides of its resonant frequency in respect to signals applied to said input circuit.
14. A system as claimed in claim 13 wherein said amplifying paths have common cathode and control electrodes and plurality of separate anodes operatively associated therewith.
15. A system as claimed in claim 13 comprising means for simultaneously varying the gain of said amplifying paths.
16. A system as claimed in claim 13 comprising means for simultaneously adjusting the gain of said amplifying paths, further means for generating a control potential varying in accordance with fluctuations of the carrier amplitude, and means to control said gain adjusting means in accordance with said control potential.
17. An electric translation system comprising an input circuit, an output circuit, a plurality of amplifiers arranged in parallel and excited from said input circuit, a tunable resonant circuit in the output of each of said amplifiers, said tunable circuits being coupled with each other and

tuned to different resonant frequencies, the resonance curves of said coupled circuits being substantially equal and overlapping so that one of said circuits acts as a receptor and another one 5 as a rejector to a desired extent, and coupling means between said tunable circuit acting as a receptor and said output circuit.

18. In a method of translating electrical oscillatory energy through a system of parallel amplifying channels of substantially equal frequency 10 response characteristics and adjustable gain, the steps of subdividing and passing said oscillatory energy simultaneously through said channels, tuning a first one of said channels to an average 15 frequency of said energy and tuning another of said channels to a different frequency within the frequency response range of said first channel, causing the subdivided oscillatory energies translated through said channels to act upon each 20 other so as to produce a resultant frequency response curve of the system of improved cut-off characteristics, adjusting the gain of at least one 25 of said channels so as to produce a desired width of said resultant response curve, and deriving the translated oscillatory energy from the output of said first channel.

19. In a method of translating electrical oscillatory energy through a system comprising a plurality of tunable resonant amplifying paths of 30 substantially equal selectivity arranged in parallel, the steps of applying said energy simultaneously to and passing it through said paths,

tuning a first one of said paths to the average frequency of said energy, tuning another one of said paths to a different frequency within the resonance curve of said first path, and causing by coupling the energies translated through said paths to act upon each other so as to produce a substantially sharper cut-off of the resultant frequency resonance curve of the system, and deriving the translated energy from the output of said first path.

20. In a method of translating a frequency band through a system composed of a plurality of amplifying filter networks arranged in parallel, said networks being of substantially equal selectivity and having adjustable gain, the steps of simultaneously applying said band to and passing it through said networks, tuning a first one of said networks to the average frequency of said band, tuning another one of said networks to a different frequency within the frequency response range of said first network, and causing the energies translated through said networks to act upon each other so as to produce an improved cut-off of the resultant frequency response curve of said system, adjusting the gain of at least one 25 of said amplifying networks so as to produce a width of said resultant curve substantially equaling the width of said frequency band, and deriving the translated frequency band from the 30 output of said first network.

JOZEF PLEBANSKI.
